SEWING MACHINE AND METHOD OF SEWING

Thomas A. Bramfitt, Watervliet, and Edward C. Pfeffer, Jr., Troy, N. Y., assignors to Cluett, Peabody & Co., Inc., Troy, N. Y., a corporation of New York

Application April 18, 1947, Serial No. 742,218

19 Claims. (Cl. 112—154)

1

This invention relates to sewing machines, and particularly to an improved method of and apparatus for sewing.

Heretofore it has been possible to compressively shrink cotton fabrics to such an extent that the residual or relaxation shrinkage is less than 1%. When garments are made of such pre-shrunk fabrics, a plurality of layers are sewed together on a sewing machine, during which threads are passed back and forth through the fabric layers repeatedly. In order to obtain a satisfactory output of garments so made, it is necessary that the sewing machines be operated at a high speed and to obtain such speeds it has been necessary to keep the thread fairly taut. The thread of the stitch is therefore under tension and when a garment sewed in this manner is subsequently laundered, the thread itself shrinks and causes a further shrinkage or compression and often puckering, of the fabric. This additional shrinkage and puckering is very pronounced when several rows of stitching are placed fairly close together within a relatively small strip of fabric, such as in the making of seams, collars and neckbands. Efforts have been made to eliminate this additional shrinkage by using a thread which is substantially non-shrinking, but as yet no satisfactory non-shrinking thread for this purpose has been discovered.

An object of this invention is to provide an improved method of and apparatus for sewing, with which this additional shrinkage and puckering of the fabric or layers united by the stitching is substantially eliminated, even when using ordinary thread; with which the sewing may be performed at the same rate and in the same manner as heretofore.

Another object of this invention is to provide an improved method of sewing, with which a desired degree of slackness in the thread of the completed stitch may be obtained automatically; with which the sewing operation may be performed at the usual or high speeds; which may be employed with stitches varying considerably in size; with which the slackness in the stitches may be uniformly distributed; and which will be relatively simple.

Another object of the invention is to provide improved mechanism for sewing, with which the tension of the thread incorporated in a line of stitching is controlled; with which a desired degree of slackness in the thread of a completed stitch may be obtained, irrespective of the speed at which the stitch is formed; with which the slackness in the thread will be uniform along

2

the completed stitching; with which the length of the individual stitches may be varied considerably as usual in sewing machines; with which a minimum modification of existing types of sewing machines will be required; with which no additional manipulation by the machine operator is required; and which will be relatively simple, practical, compact and inexpensive.

Various other objects and advantages will be apparent from the following description of one example of apparatus formed in accordance with the invention, and the novel features will be particularly pointed out hereinafter in connection with the appended claims.

15 In the accompanying drawings:

Fig. 1 is an elevation, with a few parts broken away, of part of a sewing machine constructed in accordance with this invention, certain parts of the machine being shown in intermediate positions which will be described more fully hereinafter;

Fig. 2 is another elevation of the same, the view being at approximately a right angle to that of Fig. 1;

20 Fig. 3 is an elevation of the lower part of the mechanism shown in Fig. 2, but at the opposite side of the mechanism;

Fig. 4 is an elevation of certain parts of the mechanism of Fig. 2, in one operative position;

25 Fig. 5 is a similar view, but with the parts shown in different relative operating positions;

Fig. 6 is a side elevation, on a larger scale, of parts of the machine in the act of sewing, but with the presser foot and throat plate omitted;

30 Fig. 7 is a front or face elevation of the parts shown in Fig. 6, but with the presser foot in position;

Fig. 8 is a sectional plan of the parts shown in Fig. 7, this section being taken approximately along the line 8—8 of Fig. 7; and

35 Fig. 9 is an elevation of certain of the parts separated from each other.

In the illustrated embodiment of the invention, the sewing machine is a standard type sewing machine having a head 1, which at one end mounts a vertically disposed needle bar 2 for endwise reciprocation in the usual manner. Removably mounted in the lower end of the needle bar 2 is a needle 3, the upper end of needle 3 entering a recess in the lower end of the needle bar and being secured therein by a set screw 4. The lower end portion of the needle has a thread eye 5, through which one

of the sewing threads is passed or threaded as usual in sewing machines.

Also mounted on the head 1, adjacent the needle bar 2, is a presser foot bar 6, which is yieldingly urged downwardly by a helical compression spring 7. A presser foot member 8 is fitted over the lower end of the bar 6 and it is secured removably thereon by a set screw 9 which is threaded into the side of the lower end portion of the presser foot bar 6. The shank 10 of the screw 9 is received in a slot 10 in the upper edge of one side of the member 8, and the head of the screw 9 overlaps the outer face of member 8 so that when the screw is tightened it will clamp the member 8 to the bar 6 in a manner to form a depending extension thereof. This member 8 has a forwardly extending foot 11, with a slot 12 extending from the free end of the foot 11 and beneath the lower end of the needle 3. The upper face of 20 the foot 11 is provided with a recess 13 which becomes progressively deeper from the side edges towards the inner end of the slot 12 as shown clearly in section in Figure 7.

The machine also has the usual throat plate 14 beneath the presser foot and needle, and feed dogs 15 pass upwardly through throats in the plate 14 and also beneath the presser foot so that fabric disposed on the throat plate 14 and beneath the presser foot may be fed along by small increments through the movement of the dogs 15. This is the usual work feeding mechanism on sewing machines and a thread from the usual shuttle or bobbin (not shown but beneath the throat plate) passes upwardly through the throat plate as usual in sewing machines. The dogs 15 are given a feeding movement in timed relation to the vertical movements of the needle, so that the fabric will be fed along by increments only while the needle is above the fabric.

The member 8 on the lower end of the presser bar 6 rotatably mounts a shaft 16 with its axis horizontal or parallel to the upper face of the throat plate. The forward end of the shaft 16 carries a head 17 that contains a recess 18 in its forward or end face. (See Figs. 1 and 6.) The recess 18 is open along its bottom edge. A pintle 19 extends across the recess 18 (see Fig. 7) between the opposite sides of the head 17 having the recess 18. Rockably and individually mounted on the pintle 19 are two blocks 20 and 21 disposed side by side. A wire-like finger or interponent 22 is removably secured at one end to the block 20 so as to form a downwardly depending extension thereof, and this finger 22 then extends into the recess 13 in the upper face of foot 11 and also forwardly toward the needle. At its forward end finger 22 extends in a direction cross-wise of the slot 12 as shown in Figure 7.

A similar finger 23 depends from the block 21, except that the finger 23 extends toward the finger 22 and the latter at its free end extends toward the finger 23. A torsion spring 24 has a looped part 25 intermediate of its ends, which part is disposed on one extending end of the pintle 19. One end 26 (Fig. 6) of the spring 24 is anchored to the head 17 and the other arm 27 of the spring 24 extends in front of and abuts against the finger 22. This spring 24 urges the block 20 yieldingly in a direction to carry the lower end of the block away from needle 3. A similar torsion spring 28 is mounted on the other extending end of the pintle 19, with one end

anchored to the head 17 and the other end extending toward and in front of the anchored end of the finger 23, so that the spring 28 will urge the block 21 at its lower end in a direction away from the needle 3.

The block 20 at its upper end, and adjacent the block 21, is provided with a beveled cam face 29. This cam face 29 becomes progressively deeper from the front face toward the side edge which is nearer to block 21, and the block 21 has a similar beveled cam face 30 which becomes deeper from the front face of the block as it progresses toward the block 20. Thus the cam faces 29 and 30 extend from adjoining edges and are aligned in a direction parallel to the axis of the pintle 19.

A metal stamping 31, Figs. 1 and 6, is secured to the front face of the member 8 above the head 17, and it extends forwardly above the head 17 and then downwardly in front of it, as an angular end 32. This end 32 has a concave seat 33 in its underface, facing the blocks 20 and 21, and in this seat 33 is confined a ball 34. The ball 34 rides on both beveled faces 29 and 30 when the head 17 is in a mid-rocking position, that is, the position of the parts as shown in Fig. 1, and since the ball 34 is then received in the deepest parts of the recesses formed by the bevel faces 29 and 30, the springs 24 and 28 will urge both of the members 20 and 21 in a direction to carry the fingers 22 or 23 away from the path of the needle as shown in Fig. 1. The same position of the parts is shown in Fig. 3.

If now the shaft 16 is rotated in either direction from the mid position shown in Figs. 1 to 3 in one direction, such as to the position shown in Fig. 7, the beveled face 30 will act as a cam and since the ball is held against displacement this will force rearwardly the upper end of the block 21 and move the finger 23 forwardly into a position close to, but just in the rear of the needle, as shown in Fig. 6. The rocking of shaft 16 also carried finger 23 to one side of the slot 12 in the presser foot. This tensions or stresses the spring 28. At the same time that the shaft 16 rocked in that direction into the position shown in Fig. 7, the finger 22 on the block 20 moved into a position across the slot 12 so as to bridge it as shown in Fig. 7.

A stop plate 35 is secured to the member 8 and carries spaced stop edges 36 and 37, Fig. 7, that are alternately engaged by abutments on the head 17 to limit this rocking movement of the shaft 16 in both directions. When the shaft 16 is rocked in the other direction into the other extreme position, the ball 34 will leave the beveled face 30 and will then be engaged by the beveled face 29. Thus during this rocking of the shaft 16, the beveled face 30 will move away from the ball so that the spring 28 will then urge the lower end of the member 21 yieldingly in a direction to carry the finger 23 in a direction along the line of the sewing, and the beveled or cam face 29 will be engaged by the ball 34 which serves to rock the block 20 in a direction to carry finger 22 forwardly and to one side of the slot

12. This movement is limited by the stop plate 35.

The shaft 16 extends through the member 8, in which it is rotatably mounted, in a direction (Fig. 1) parallel to the direction of feed of the fabric, also in a direction away from the needle 3. At the opposite face of the member 8, the shaft 16 carries a member 38 (Figs. 1 and 9) which is fixed thereon in any suitable manner such as by set screw 39. Disposed on shaft 16 between the member 38 and the member 8 is a cam 40, against which the member 38 abuts. This cam 40 is generally cylindrical, but is provided in an edge thereof with a notch 41 (Figs. 4 and 5) which receives a tongue 42 (Figs. 1 and 9), carried on the abutting face of the member 38 and which provides a driving connection between the member 38 and the cam 40. The cam 40 is provided with a passage 43 from end face to end face that terminates in a direction about shaft 16 at approximately diametrically opposite sides of the shaft 16. The cam 40 has a central aperture 44 through which the shaft 16 passes. That wall of the passage 43 nearest to the outside circumference is arcuate with a center of curvature at the center of the passage 44. The opposite or inner margin of the passage 43 is generally V-shaped, as at 45, with the center of the V approximately mid-way between the terminals or limits of the passage 43.

An arm 46, Fig. 1, is provided at one end with a boss 47, which has a central passage 48 that is fitted over the lower end of the needle bar 2. A set screw 49 in the boss 47 engages the bar 2 and secures the arm 46 removably to the needle bar for vertical reciprocation therewith, yet the arm may be adjusted to a limited extent along the needle bar. The arm 46 extends to one side of and clears the presser member 6, and at its other end it is apertured to receive the threaded end 50 of a post 51. Nuts 52 are threaded on the end 50 at opposite sides of the arm 46, so that when the nuts 52 are tightened against the arm 46, they will secure the post 51 rigidly but adjustably to the arm 46 in a position to extend upwardly from arm 46, as shown in Fig. 1. The post 51 above the threaded end 50 is preferably made square or rectangular in transverse cross-section, and a runner or shoe 53 is slidingly mounted on this upper end the post 51. The runner 53, on its face toward the presser member 6, carries a stud 54 which pivotally mounts a link 55. The link 55 is confined on the stud 54 in any suitable manner, such as by a nut 56 which is threaded upon a reduced end of the stud 54. The engagement of this nut against a shoulder on the stud 54 prevents tightening of the nut 56 sufficiently to retard free pivotal movements of link 55. The link 55 depends from the stud 54 and at its lower end it slidingly receives a rod 57 which is secured thereon in different positions by a set screw 58. The lower end of the rod 57 is bent laterally as at 59 to extend toward the member 8. The cam 40 is provided with a notch or recess 60 (Figs. 1 and 9) in the face towards the member 38 and in its upper surface, for approximately $\frac{1}{2}$ the circumference thereof, and the lower end of the rod 57 is received in this notch 60, so that the bent or angular end 59 may enter the passage 43 and be confined therein by member 38. This end 59 rides freely in the passage 43, and the lower surface 61 (Fig. 9) of the angular end 59 is V-shaped or downwardly convergent.

Disposed along the post 51, Figs. 1 and 2, in

a face thereof, are two spring ball catch units 62, arranged one above the other, and each unit has a ball 63 which is urged outwardly partly out of a shell or casing 64 by a spring 65. These spring ball catches are well known in the art and may be purchased in the open market. The balls extend outwardly for only a slight extent beyond the casing, as shown in Fig. 1, and when the runner 53 is moved along the post 51 it will engage and force the balls 63 inwardly. The balls, when within the passage of runner 53, exert frictional pressure on the passage. After the runner passes both of the balls during its relative upward movement on post 51, it will be held against descent past the balls by the resistance of the balls to pressure inwardly, the weight of the runner 53 and the link 55 and rod 57 carried thereby being insufficient to force the runner past the balls. When the runner 53 is below both of the balls 63 then it falls freely under the action of gravity. Only one ball catch is necessary, but the use of two is more certain to prevent accidental release of the runner. Stops 66 on head 17 beneath the blocks 20 and 21 limit the movements of these blocks under the urging of springs 24 and 28.

In the use of this apparatus, the superposed layers of fabric to be united (designated F collectively) are disposed beneath the presser foot 30 (Figs. 6 and 7) and over the throat plate 14 as usual in sewing machines. The lower thread 66 which is carried by a bobbin (not shown) beneath the throat plate as usual in sewing machines is pulled upwardly through the throat 35 in the throat plate. The upper thread 67 supplied from a spool on the sewing head, after passing through the usual thread tensioning means (not shown), is threaded through the eye 5 of the needle 3 as usual in sewing machines. In a sewing operation, initiated in the usual manner, the lower or pointed end of the needle 3 pierces the fabric layers to carry the eye 5 and upper thread 67 beneath the fabric layers and there the upper thread 67 is interengaged with the lower thread 66 as usual in sewing machines. As the needle 3 is withdrawn from the fabric layers the thread 67 is pulled upwardly and tensioned. While the needle is elevated the dogs 15 are operated in a manner usual in sewing machines to feed the fabric layers F to the left 40 in Figs. 1 and 6, a distance equal to a desired length of stitch, which length may be varied by the usual feeding mechanism found on sewing machines. The upper thread 67 is then in the position shown in Figs. 6 to 8.

During this usual sewing operation just described, the additional mechanism constructed in accordance with this invention is effective to alternately project the fingers 22 and 23 beneath the upper thread 67 leading to the needle from the fabric so that whenever the needle descends for a new stitch, one of the fingers 22 or 23 will be beneath the upper thread 67 of that stitch, as shown by the finger 22 in Figs. 6 and 7. When the needle 3 descends for the next stitch, the other finger 23 will move beneath that portion of the thread 67 which extends from the fabric to the eye of the needle, in a manner to be explained presently, and as finger 23 moves beneath the thread 67 and across the slot 12 in the presser foot, the finger 22 will be removed from beneath the upper thread 67 of the previously completed stitch, and then moved forwardly ready to again move beneath the thread 70 67 in the next following stitch.

To alternately place the fingers 22 and 23 under the thread of successive stitches in this manner, and then remove them after the stitches have been completed, provision is made to rock the head 17 alternately back and forth, as will now be explained. As the needle bar 2 ascends into the position shown in Fig. 1 at the end of a stitch formation, it carries with it the bar 46 and post 51. During the stitch formation the runner 53 is above the spring balls 63 as will appear later, so that as the post 51 rises it will carry with it the runner 53, the link 55 and the depending rod 57. During this ascent, when the angular end 59 on the lower end of rod 57 engages the arcuate surface of the passage 43 in cam 40 as shown in Figs. 1, 2 and 3, the rod 57 is held against further ascent and through the link 55 the runner 53 is held against further ascent. The post 51 continues to rise, however, and the runner 53, which is held, then is relatively forced past the balls 63, during which the balls are pressed inwardly, and as soon as the runner 53 clears the lower ball 63 it falls, carrying with it the link 55 and rod 57. The cam 40 when idle always remains in either the Fig. 4 or Fig. 5 position, because of stop edges 36 and 37 and the weight of runner 53.

Assuming that cam 40 is in the position shown in Fig. 4, it will be observed that as the rod 57 rises, the angular end 59 will ride along one side of the V-shaped surface 45, pass the apex of the V wall, and then swing by gravity, aided by the camming action of the arcuate wall of the passage 43, into a vertical position, slightly to the right of the apex of the wall 45, so that when the runner 53 is released from the lowermost ball 63, as just explained, and falls, the angular end 59 will pass to the right of the apex of wall 45 and ride down the opposite wall of the V, engaging in the right hand terminus of the passage 43. Thereupon the weight exerted on this right hand terminus by the runner 53 and link 55, will rock the cam 40 through the intermediate position shown in Figs. 1, 2 and 3 from the extreme position shown in Fig. 4 to the other extreme position shown in Fig. 5. Engagement of head 17 with edges 36 and 37 limits rocking movements of shaft 16 and cam 40.

The cam 40 rocking in this manner also rocks shaft 16, to which it is coupled by member 38, through a corresponding angle (clock-wise in Fig. 7) and this movement moves the finger 23 beneath the thread 67 and across the slot 12 in the presser foot. By this same movement the finger 22 is removed from beneath a completed stitch. During this movement of cam 40 the ball 34 moves out of contact with the beveled face 30 on the block 21, so that the finger 23 may move downwardly, under the urging of the spring 28, into a position across and over the slot 12, and then when the needle next descends, the thread 67 will be pulled downwardly over the finger 23. During this same rocking movement of the shaft 16 the beveled cam face 29, moves beneath the ball 34 and since the cam face 29 is above the pintle 19, the block 20 will be rocked on the pintle 19 in a direction to carry the finger 22, which is then clear of the previously completed stitch, in a direction to move the finger 22 forwardly, immediately at the rear and one side of the needle, and ready to move beneath the thread 67 as soon as the needle again rises and the shaft 16 is rocked back into its former position which

is represented by the position of the cam 40 in Fig. 4.

While the finger 23 is across the slot 12 of the presser foot, the needle again descends and pierces the fabric, the upper and lower threads again are interlocked, and then the needle rises and tensions the upper thread. During this operation, the finger 23 is stitched to the fabric, but during the next stitch forming operation the finger 23 is withdrawn, which leaves a slack in the thread of the completed stitch, as shown in Fig. 6. During each descent of the needle 3, the arm 46 is also carried downwardly, but since the runner 53 is limited in its downward movement by the engagement of the angular end 59 with the right hand terminus of the cam in Fig. 5, the post 51 during its descent will carry its balls 63 below the runner 53. Thereafter when the needle again rises the balls 63 will engage with the lower edge of the runner and move the runner with the post 51 thus raising the rod 57.

As rod 57 rises, the lower angular end 59 will ride along one side of the V-shaped wall 45, and then will be swung to the left in Fig. 5 by gravity and the camming action of the arcuate surface defining the upper limit of the passage 43, but when the passage 43 limits further upward movement of rod 57, the continued movement of post 51 with the needle bar will cause the balls 63 to pass above the runner 53. The runner then immediately falls by gravity, and during its descent the angular end 59 at the lower end of the rod 57 will engage with the other side of the V-shaped wall 45 and be cammed thereby to the left into engagement with left hand terminus of the passage 43. The inertia and weight of the runner 53, link 55 and rod 57 will then rock the cam 40 from the Fig. 5 to the Fig. 4 position, during which the cam 40 passes through the intermediate position shown in Figs. 1, 2 and 3.

This movement rotates the shaft 16 back into its former position shown in Figs. 6, 7, and 8, during which finger 23 is removed from beneath a completed stitch and moved forwardly by the ball 34, ready for movement beneath the thread 67. At the same time finger 22 is moved beneath the thread 67 and downwardly over the slot 12, so that when the needle 3 next descends, the finger 22 will be sewed against the superposed layers of the fabric as shown in Figs. 6, 7 and 8. Thus this cycle will be repeated over and over until the row of stitching is completed.

It will be noted that while each stitch is being formed there will be a finger 22 or 23 secured beneath the upper thread 67 and against the upper face of the superposed fabric layers, and then after the thread has been tightened the finger is removed from beneath the completed stitch, which provides a desired degree of slackness in the thread of the completed line of sewing or stitching. In this manner the sewing may proceed at the usual rate during which the upper thread 67 is tightened, yet, as the fingers are removed from beneath the thread, a small amount of slackness will be left in the stitch thread. Thereafter when the sewed fabrics or layers are washed the shrinkage of the thread will not cause a further shrinkage of the fabric or a puckering thereof. It will also be observed that this improved and added mechanism will operate in the same manner, even though the length of the stitch is varied by varying the extent of the usual feeding mechanism of sewing machines.

It will be understood that in Fig. 6 the presser foot is not shown, in order that the slackness in

the completed stitching and the position of the finger 22 may be seen. It will also be understood that the intermediate position of the shaft 16 in Figs. 1, 2 and 3 is merely an intermediate position through which the parts move as the cam 40 moves between the positions shown in Figs. 4 and 5.

It will also be understood that various changes in the details, materials and arrangements of parts, which have been herein described and illustrated in order to explain the nature of the invention, may be made by those skilled in the art within the principle and scope of the invention as expressed in the appended claims.

We claim:

1. In a sewing machine of the type having a throat plate, a feed dog operating upwardly through said plate to feed the work over said plate by increments, a pressure foot, a head, a needle, a bar mounting said needle and means operating said needle bar and needle vertically in timed relation to the movement of said dog to sew, that improvement which comprises a finger disposed with its free end above and across the line of stitching immediately in the rear of the needle, a member mounting said finger for limited movement in directions sidewise of said line of stitching to carry the free end of said finger back and forth across the axis of the line of stitching in proximity to the work on said throat plate and also for movement in the direction of feed, and an operating connection from the needle operating means to said member for moving the free end of said finger across said line of stitching at the rear of the needle beneath the thread from the needle to the work, and removing it from beneath the thread during the formation of another stitch.

2. In a sewing machine of the type having a throat plate, a presser foot for confining work to said plate, a needle which reciprocates vertically and carries a thread through the work step by step, means for reciprocating the needle endwise, and a feed dog operating upwardly through said plate for feeding the work along by increments after each piercing of the work by the needle and its thread, that improvement which comprises a finger having a free end disposed at the rear of the needle and beneath the thread from the needle to the work generally parallel to the face of said plate and crosswise of the direction of feed of the work, a support mounting said finger for movement back and forth in the direction of the line of feed, a member mounting said support for rocking movement in a direction crosswise of the line of feed to carry the free end of the finger back and forth across and in close proximity to the line of feed, an operative connection from said needle-reciprocating means to said mounting for rocking the latter in a direction crosswise of the line of feed in one direction only at each complete reciprocation of the needle, and an element acting on said support, as the support rocks to remove said free end of said finger from across the line of feed, for positively moving said free end forwardly towards said needle and for releasing it when it rocks in the opposite direction, whereby when said member is rocked in one direction to carry the free end of the finger, across the feed line said finger will be sewed by said thread to the work, and when said member is rocked in the opposite direction from across the feed line, said finger will be withdrawn from beneath the thread of the

completed stitch to leave slack in the thread of the completed stitch from which it is withdrawn.

3. In the method of uniting layers of fabrics by the usual stitching, in which a thread is passed through the superposed fabrics at spaced intervals by a needle and the fabrics moved beneath the needle by increments while the needle is withdrawn from the fabric, that improvement therein for providing selected slackness in the thread of the uniting stitch, which comprises the steps, during the sewing, of placing an individual interponent at intervals beneath the thread section extending from the fabric to the needle while the needle is above the fabric and before the needle again enters the fabric, continuing the sewing with the interponent so placed to sew the interponent to the fabric, feeding the fabric with the engaged interponent in a feeding direction ready for another stitch formation, and withdrawing the interponent from beneath the thread in the stitch after the stitch has been completed, and during the formation of another stitch.

4. In the method of uniting layers of fabrics by the usual stitching, in which a thread is passed through the superposed fabrics at spaced intervals by a needle and the fabrics moved beneath the needle by increments while the needle is withdrawn from the fabric, that improvement therein for providing selected slackness in the thread of the uniting stitch, which comprises the step, during the sewing, of placing a plurality of individual interponents, in succession beneath that portion of the thread extending from the fabric to the needle while the needle is away from the fabric and before the needle again enters the fabric, sewing the interponents in alternate succession to the fabric, moving the interponents with the moving fabric to which stitched, in a feeding direction and withdrawing each interponent in similar succession from beneath the thread of the completed stitch, while another interponent is being sewed to the fabric.

5. In the method of uniting layers of fabrics by the usual stitching, in which a thread is passed through the superposed fabrics at spaced intervals by a needle and the fabrics moved beneath the needle by increments while the needle is withdrawn from the fabric, that improvement therein for providing selected slackness in the thread of the uniting stitch, which comprises the steps of sewing to the fabric on the exposed face thereof, by the needle and the thread which unites the fabric layers and in the same operation, a plurality of individual interponents, one beneath each of selected stitch loops in succession, and pulling the interponents in the same succession from beneath the stitching completed thereover, during subsequent sewing operations.

6. In the method of uniting layers of fabrics by the usual stitching, in which a thread is passed through the superposed fabrics at spaced intervals by a needle and the fabrics moved beneath the needle by increments while the needle is withdrawn from the fabric, that improvement therein for providing selected slackness in the thread of the uniting stitch, which comprises the steps of inserting individual interponents beneath that portion of the thread extending from a completed stitch to the needle while the needle is disengaged from the fabric, alternately from opposite sides of the line of stitching, sewing the interponents so positioned in succession to the fabric with a single interponent beneath each thread loop of a stitch moving each interponent with the fabric to which

it is sewed, and pulling the interponents from beneath the stitching completed thereover, in the same succession but alternately from opposite sides of the line of stitching, during an operation of the needle subsequent to that which sewed that interponent to the fabric.

7. In the method of uniting layers of fabrics by the usual stitching, in which a thread is passed through the superposed fabrics at spaced intervals by a needle and the fabrics moved beneath the needle by increments while the needle is withdrawn from the fabric, that improvement therein for providing selected slackness in the thread of the uniting stitch, which comprises the steps of stitching separate fingers to the fabric layers in succession by the same thread and operation that unites said fabric layers, moving the fingers with the fabric portion to which they are sewed during the feeding operations of the fabric, and then removing said fingers from beneath the thread of the stitching after the needle has started its descent to sew another finger to the fabric to leave slack in that thread of the completed stitch.

8. In the method of uniting layers of fabrics by sewing in which a thread is carried through the superposed fabrics at spaced intervals and the fabrics moved beneath the needle between successive needle movements through the fabrics and while the needle is clear of the fabrics, that improvement therein for providing selected slackness in the thread of the uniting stitch so formed, which comprises confining a finger-like interponent repeatedly to the fabrics by a thread in the same sewing operation and by the same thread that unites the fabrics, with the thread passing through the fabrics at the sides of and free of the interponent, and withdrawing the finger from beneath each finger-confining stitch after formation of at least one subsequent stitch has started.

9. In a sewing machine of the type having a throat plate, a presser foot for confining work to said plate, a needle which reciprocates vertically and carries a thread through the work step by step, means for reciprocating the needle endwise, and a feed dog operating upwardly through said plate for feeding the work along by increments after each piercing of the work by the needle and its thread, that improvement which comprises a finger having a free end disposed to extend approximately crosswise of and in proximity to the line of sewing and immediately in the rear of the needle, means mounting said finger for movement in a direction to carry its free end crosswise of said line of sewing between one position at one side of said line and another position across said line, and also for limited movement in a direction back and forth along said line between one position in which said free end is beneath the position of the sewing thread extending from a completed stitch to said needle while the needle is withdrawn from the work, and means operated in timed relation to the needle movements for moving said finger to carry its free end crosswise of said line of sewing to a position at one side of said line when said needle is away from said work in one operation and back into a position across said line when the needle is away from said work in another operation, repeatedly, and means urging said free end of said finger towards said needle when it is at said one side of said line of sewing, in a position to move beneath the sewing thread when it is again moved into its position across said line of sewing.

10. In a sewing machine of the type having a throat plate, a feed dog operating upwardly

through said plate, a head, a pressure foot, a needle bar, and a needle carried by said bar and reciprocated vertically thereby in synchronized relation to the movements of said feed dog, that improvement which comprises a member mounted to rock about an axis generally parallel to the direction of feed of fabric by said dog, also to swing about an axis crosswise of said direction of feed, and having a projecting finger disposed just above the pressure foot and adjacent said needle, said finger being movable, during its rocking with said member, between the thread and needle while the needle is above the fabric, remaining in that position while the needle descends and a stitch is formed over said finger, and moving along the line of sewing with the work through rocking of said member on said crosswise axis, and means operated in timed relation to the movements of the needle for rocking said member about said axis parallel to the direction of feed to carry said finger from beneath the stitch formed thereover, said member being yieldingly urged towards the needle about said crosswise axis when pulled from beneath said stitch.

11. In a sewing machine of the type having a throat plate, a needle, and means for feeding fabrics to be sewed together step by step beneath the needle while the needle is above the throat plate, that improvement which comprises a finger having a free end extending crosswise of the direction of the feed of the fabrics at the rear of the needle, means mounting said finger for movement of its said free end into and out of a position across the fabrics at the rear of the needle and beneath the thread passing from the last formed stitch to the needle and also for movement in the direction of the line of feed of the fabrics, whereby when said finger is in its said position said finger will be sewed to the fabrics and then may move with the fabrics along said line of feed, and means operable in timed relation to the movement of said needle for moving said finger endwise beneath the thread from said fabrics to the needle during the formation of a stitch, and then removing it endwise from beneath the thread of the stitch after the stitch has been completed and fully tightened, so as to leave slack in the thread of a completed stitch.

12. In a sewing machine of the type having a throat plate, feeding means for feeding superposed fabric layers to be sewed together across the throat plate, a needle disposed above said throat plate and fabric, and operable through the fabric and backwardly for carrying a thread through the fabric for interconnection with a lower thread, that improvement for causing slack to be formed in the thread of any completed stitch which comprises a finger having its free end extending generally in a direction crosswise of the direction of feed of the fabric layers, means mounting said finger for movement in said crosswise direction, and also in the direction of feed of the fabrics, means for interposing said finger between said layers and a thread of said stitch during the formation of that stitch, and then removing it from between the thread and fabric after that stitch has been completed and has moved the finger along said direction of feed with the fabrics, said means being operated in timed relation to the movement of said needle.

13. In a sewing machine of the type having a throat plate, feeding means for feeding superposed fabric layers to be sewed together across the throat plate, a needle disposed above said throat plate and fabric, and operable through the fabric and backwardly for carrying a thread

75

through the fabric for interconnection with a lower thread, that improvement for causing slack to be formed in the thread of any completed stitch which comprises a finger having its free end extending generally in a direction crosswise of the direction of feed of the fabric layers, means mounting said finger for movement back and forth across the line of sewing, immediately in the rear of the needle and also for movement with the fabrics by said feeding means, and means for operating said needle and said finger in timed relation to each other, and for interposing said finger between said layers and a thread of said stitch during the formation of that stitch, and then removing it from between the thread and fabric after that stitch has been completed and has been moved with said fabrics in a feeding operation, and, while said needle is withdrawn from said fabric.

14. In a sewing machine of the type having a throat plate, feeding means for feeding superposed fabric layers to be sewed together across the throat plate, a needle disposed above said throat plate and fabric, and operable through the fabric and backwardly for carrying a thread through the fabric for interconnection with a lower thread, that improvement for causing slack to be formed in the thread of any completed stitch which comprises a pair of fingers having free ends extending towards each other from opposite sides of the line of sewing, and in a direction crosswise of the direction of the feed of the fabric layers beneath the needle, means mounting said fingers for movement to carry said free ends alternately across the line of sewing and between the fabric and a thread of the stitch, during the formation of that stitch, so that the fingers may be alternately and successively sewed to the fabric by the thread, whereby when either finger is interposed between a thread and the fabric layers in the formation of a stitch, the other finger will be removed from between the fabric and the thread of a completed stitch to provide slackness in the thread of the completed stitch, and means for moving said fingers back and forth in timed relation to the movement of said needle.

15. The method of sewing fabric plies to prevent subsequent puckering and compression of the sewed plies by the shrinkage of the thread when the sewed plies are laundered, which comprises progressively sewing the fabric plies, feeding them along step by step, and concurrently during the sewing, disposing interponents in succession upon the fabrics beneath the thread that unites the fabric plies so that the interponents will be confined to the plies and move with them during their feeding movements, and removing the sewed interponents from completed stitches in similar succession during the same sewing operation in the formation of another subsequent stitch by the same thread.

16. In a sewing machine of the type having a throat plate, a presser foot for confining work to said plate, a needle which reciprocates vertically and carries a thread through the work step by step, means for reciprocating the needle endwise, and a feed dog operating upwardly through said plate for feeding the work along by increments after each piercing of the work by the needle and its thread, that improvement which comprises a finger having a free end disposed to extend approximately crosswise of and in proximity to the line of sewing and immediately in the rear of the needle, means mounting said finger for movement in a direction to carry its free end crosswise of said line of sewing between one position at one

side of said line and another position across said line, and also for limited movement in a direction back and forth along said line between one position in which said free end is beneath the position of the sewing thread extending from a completed stitch to said needle while the needle is withdrawn from the work, and means operated in timed relation to the needle movements for moving said finger to carry its free end crosswise of said line of sewing to a position at one side of said line when said needle is away from said work in one operation and back into a position across said line when the needle is away from said work in another operation repeatedly.

17. In a sewing machine of the type having a throat plate, a feed dog operating upwardly through said plate for feeding, step by step, a fabric resting thereon, a head, a pressure foot, a needle bar reciprocating vertically in a synchronized relation to the movement of said feed dog, and a needle carried by said bar, that improvement which comprises a shaft carried by said pressure foot and extending in the direction parallel to the direction of the feed of the fabric by said feed dog, a pair of arms hinged on the end of the shaft nearest the needle for rocking movement with the shaft about the shaft axis and also for individual rocking on said shaft about an axis disposed in a plane transverse to the axis of said shaft, a finger carried by the lower end of each arm and extending toward the finger on the other arm, so that as the shaft is rocked the free ends of the fingers will be carried alternately back and forth across the direction of feed travel of the fabric and in close proximity to any fabric on said throat plate in feeding position, said fingers being disposed at one side of the needle and movable, by rocking of the shaft, alternately into and out of positions beneath a thread leaving the last formed stitch and the needle, a member on the pressure foot for engaging with said arm alternately when said shaft is rocked and camming said arms in directions to carry the fingers alternately towards the needle path, each finger being cammed towards the needle when its free end is furthest from the line of stitching, and released when the finger is moved, by rocking of the shaft, across the line of stitching, and an operating connection from said reciprocating needle to said shaft for rocking said shaft alternately in opposite directions to place said fingers alternately across the line of stitching.

18. In a sewing machine of the type having a throat plate, a feed dog operating upwardly through said plate for feeding, step by step, a fabric resting thereon, a head, a pressure foot, a needle bar reciprocating vertically in a synchronized relation to the movement of said feed dog, and a needle carried by said bar, that improvement which comprises a shaft carried by said pressure foot and extending in the direction parallel to the direction of the feed of the fabric by said feed dog, a pair of arms hinged on the end of the shaft nearest the needle for rocking movement with the shaft about the shaft axis and also for individual rocking on said shaft about an axis disposed in a plane transverse to the axis of said shaft, a finger carried by the lower end of each arm and extending toward the finger on the other arm, so that as the shaft is rocked the free ends of the fingers will be carried alternately back and forth across the direction of feed travel of the fabric and in close proximity to any fabric on said throat plate in feeding

position, said fingers being disposed at one side of the needle and movable, by rocking of the shaft, alternately into and out of positions beneath a thread leaving the last formed stitch and the needle, a member on the pressure foot for engaging with said arms alternately when said shaft is rocked and camming said arms in directions to carry the fingers alternately towards the needle path, each finger being cammed towards the needle when its free end is furthest from the line of stitching, and released when the finger is moved, by rocking of the shaft, across the line of stitching, a member fixed on said shaft and having therein a cam groove extending partly around the axis of the shaft, the inner surface of the groove between its ends being approximately V shaped, a shoe, a link hinged to said shoe for rocking on a horizontal axis, depending from the shoe and having a lateral terminal at its lower end running in said groove, and means coupling the needle bar and shoe for lifting the shoe each time the needle is lifted and then dropping it.

19. In a sewing machine of the type having a throat plate, a feed dog operating upwardly through said plate, a head, a pressure foot, a vertically reciprocating needle bar operating in a synchronized relation to the movements of said feed dog, and a sewing needle carried by said bar, that improvement comprising a shaft rockably mounted on said pressure foot and having at one end a cam groove extending part way around the rocking axis of the shaft, the inner wall of said groove between its ends being generally V-

shaped, an upright member coupled to said needle bar for reciprocation therewith, a shoe slideable upon said reciprocating member, a link hinged to said shoe on a horizontal axis, depending from the shoe, and having a horizontally extending terminal at its lower end, said terminal running freely in said cam groove so that as the shoe is raised and lowered, said terminal will engage alternately with opposite ends of said groove and rock the feed shaft alternately in opposite directions, a coupling between said upright member and shoe for connecting them, for movement together with the needle bar, when the latter is in its lowermost position, and for lifting of the shoe during ascent of the needle and dropping it before the needle bar completes its upward travel, and means also carried by the shaft for alternately interposing a pair of fingers beneath the thread in the formation of a stitch and removing one finger when the other finger is inserted beneath the thread.
